CLAIM

The ornamental design of a structural extrusion, as shown and described.

DESCRIPTION

FIG. 1 is a perspective view of the structural extrusion showing our new design;

FIG. 2 is an end view of the structural extrusion showing our new design;

FIG. 3 is a side elevation view of the structural extrusion showing our new design;

FIG. 4 is a side elevation view of the structural extrusion opposite to that shown in FIG. 3 and showing our new design;

FIG. 5 is a front elevation view of the structural extrusion showing our new design; and,

FIG. 6 is a rear elevation view of the structural extrusion showing our new design.

FIG. 3

FIG. 2

FIG. 1

FIG. 6FIG. 5FIG. 4
